CONTAINER CAP

Albert H. Jung, Flushing, N. Y., assignor to Victor Industries Corporation, Brooklyn, N. Y., a corporation of New York

Application May 1, 1948, Serial No. 146,116

Term of patent 14 years

(Cl. D58—26)

To all whom it may concern:

Be it known that I, Albert H. Jung, a citizen of the United States, and resident of Flushing, Queens County, city and State of New York, have invented a new, original and ornamental Design for a Container Cap, of which the following is a specification, reference being had to the accompanying drawing, forming a part thereof, wherein:

Fig. 1 is a top plan view of a container cap, showing my new design.

Fig. 2 is a side elevational view thereof.

The characteristic feature of the design resides in the series of circumferentially arranged adjacent square pyramids, each having a horizontal axis intersecting the axes of the remaining pyramids at a common point, the upper horizontal edge of the base of each pyramid forming an edge of the base of a polygonal pyramid hav-

ing a vertical axis passing through said common point, as shown in the drawing.

I claim:

The ornamental design for a container cap, substantially as shown and described.

ALBERT H. JUNG.
